(57) **CLAIM**

The ornamental design for a flashlight mount, as shown and described.

DESCRIPTION

FIG. 1 is a perspective view of a flashlight mount showing my new design;

FIG. 2 is another perspective view of the flashlight mount shown in FIG. 1;

FIG. 3 is a front elevational view of the flashlight mount shown in FIG. 1;

FIG. 4 is a right side elevational view of the flashlight mount shown in FIG. 1;

FIG. 5 is a rear elevational view of the flashlight mount shown in FIG. 1;

FIG. 6 is a left side elevational view of the flashlight mount shown in FIG. 1;

FIG. 7 is a top plan view of the flashlight mount shown in FIG. 1; and,

FIG. 8 is a bottom plan view of the flashlight mount shown in FIG. 1.

The broken lines shown in the Figures are included for the purpose of illustrating portions of the flashlight mount that form no part of the claimed design.

1 Claim, 7 Drawing Sheets
